UNITED STATES PATENT OFFICE.

WM. L. YOUNG, OF MUSCATINE, IOWA.

MACHINE FOR CUTTING BARREL-HEADS.

Specification of Letters Patent No. 12,452, dated February 27, 1855.

To all whom it may concern:

Be it known that I, WILLIAM L. YOUNG, of the city of Muscatine and county of Muscatine and State of Iowa, have invented a new and useful Improvement on a Machine for Circling and Leveling Barrel-Heads; and I do hereby declare that the following is a full, clear, and exact description of the construction and operation of the same, reference being had to the annexed drawing, making a part of this specification.

Drawing, Figure 1, No. 1, loose pulley; No. 2, light pulley; No. 3, driving plane surface face plate; No. 4, counter face plate, with a circular row of center bearing quarter elliptic springs bolted to the edge; No. 5, steel center, with a round point on which counter face plate (No. 4) runs; No. 6, a pronged coupling, retained on the center (No. 5) by a shoulder and bolted to counter face plate (No. 4); No. 7, hand wheel; No. 8, roller posts, through which the levers (No. 10) pass; No. 9, rests, supporting roller posts and levers; No. 10, levers, to the front end of which are attached cutters (Nos. 12 and 13); No. 11, post standing directly under face and counter plates (Nos. 3 and 4) to be raised by means of lever (No. 12) to retain the barrel head in its proper position until fastened by operation of hand wheel (No. 7); No. 12, lever, attached to the bottom of post (No. 11) operated by placing the foot upon it; No. 13, right hand tool, bolted to the end of lever (No. 10), for cutting the inner circle and bevel of the barrel head; No. 14, left hand tool, for cutting the outer circle and bevel of the barrel head; No. 15, frame, upon which the above described machine stands; No. 16, a circular row of twelve, more or less, center bearing quarter elliptic springs, with projecting points for pressing every part of the barrel head firmly against the driving face plate, (No. 3), and set in indentations in the counter-face plate (No. 4) giving them the proper direction.

The operation of the above described machine consists first in placing the foot on the lever (No. 12), raising the post (No. 11) until it comes in contact with the face plate (No. 3) retaining the different pieces of the barrel head in a proper position until by the operation of the hand-wheel the projecting points of the center bearing springs are brought in contact with the different pieces forming the barrel head pressing them firmly against the plane surface of the driving face plate (No. 3). By this pressure, pieces of different thickness may be cut at the same time the springs yielding readily to the thicker portions of the material. The only form of cutters used with success is the right, or one cutting the inner circle and bevel in the form of a gouge—and the left, or one cutting the outer circle and bevel of the barrel head in the form of a V. Any sized barrel head required may be cut by this machine from 16 to 24 inches in diameter, by withdrawing the rest. A long or short bevel may be given by enlarging or contracting the distance between the rests at the outer end; the cutting being done from the center toward the circumference, bringing the operation of the cutter upon the chip instead of upon the solid portion of the barrel head. The average number of heads cut by this machine, by one man, in ten hours is 800.

Your petitioner hereby enters his disclaimer to all or any portions of the machine aforesaid, for which a patent or patents may have been granted previous to the filing of this petition.

What I claim as my invention and desire to secure by Letters Patent, is—

The centrally pressing toothed springs, as arranged; and also their combination with a disk free to vibrate on its axle, for the purposes set forth.

WM. L. YOUNG.

In presence of—
L. D. PARMER,
W. D. AMENT.
